ATTORNEY

UNITED STATES PATENT OFFICE.

WILLIAM N. O'ROURKE, OF JERSEY CITY, NEW JERSEY.

PENCIL-LEAD HOLDER.

Application filed May 27, 1920. Serial No. 384,558.

To all whom it may concern:

Be it known that I, WILLIAM N. O'ROURKE, a resident of Jersey City, in the county of Hudson and State of New Jersey, have invented certain new and useful Improvements in Pencil-Lead Holders, of which the following is a specification.

This invention relates in a general way to handwriting instruments wherein lead is employed for producing the desired manuscript, and it especially appertains to holders of the magazine type that are designed to contain a supply of pencil leads, adapted to be manually positioned in the tip of the holder and projected therefrom, for use one at a time in succession.

Primarily, the invention has for its object to produce a writing instrument of the type mentioned having an ejector so mounted therein as to permit the employment of a comparatively long pencil lead in a casing of ordinary size, or optionally a casing of reduced longitudinal dimension with a lead of customary length.

Another object is the production of a writing instrument of the character set forth including an ejector and a protective carrier therefor conjointly engaging a pencil lead guide, that will coact therewith in feeding the lead out of the holder.

A further object is the provision of a writing instrument of the nature described, from which the pencil lead can be projected through the said guide by merely turning the tip or point thereof, so as to draw out the said ejector with its carrier acting as a slide impeller and support.

Still another object is to provide a writing instrument of the class referred to embodying an alternative construction to the above, in which the guide will be stationary, and the lead advanced therein by the ejector, upon translating the carrier thereof from the rear end of the holder.

A still further object is to supply a writing instrument of the genus alluded to, combining both of the preceding constructions, in such a manner that the projection of the lead may be effected by turning, at option, either the guide or the ejector-carrier, from

the opposite ends of the holder respectively, and if desired, the guide and the carrier simultaneously.

An additional object is to devise a practical pencil lead holder composed of but few parts, easily constructed and readily joined together, involving no complex arrangement nor intricate mechanism, not liable to get out of order, besides being characterized by strength, and susceptible of low cost of manufacture.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawing, wherein like parts are designated by the same reference characters throughout the several views.

In the said drawing,

Fig. I is a substantially central longitudinal section of a holder embodying one form of the invention, wherein the feed of the pencil lead is effected by rotating the holder's point;

Fig. II is a transverse section on the line II-II of Fig. I, looking toward the point of the holder, as indicated by the arrows;

Fig. III is a similar cross-section on the line III-III of Fig. I, looking in the same direction, likewise pointed out by a pair of arrows;

Fig. IV is a substantially central longitudinal section representing a modified construction, in which the feed of the lead depends upon the rotation of an element located at the rear end of the holder;

Figures V, VI, and VII are transverse sections, respectively taken from the lines marked V-V, VI-VI, and VII-VII in Fig. IV, looking forwardly with relation to the point of the holder, as indicated by the arrows in each instance;

Fig. VIII illustrates, again in substantially central longitudinal section, a further modified form of the invention, the chief

feature whereof consists in that the lead may be fed from the holder by rotating either or both of its ends; and

Fig. IX is a cross-section on the line 5 IX—IX of Fig. VIII, looking as before, in the direction indicated by the arrows, toward the point of the holder.

It will be observed that all of the above-mentioned figures are drawn to a greatly enlarged scale, such that the longitudinal sections had to be shown as broken to permit laying them out within the space prescribed. The exaggerated dimensions of the holder, it is understood, bring out most clearly the 15 nature of the invention as a whole, and its several component parts as well, in a limited number of views, without resorting to a multiplicity of detail figures in order to afford an adequate comprehension of the improvements involved.

Generally described, the invention comprises an outer casing of conventional configuration, having a magazine with compartments for separately holding a number 25 of pencil leads at one end, and a feed-tube for a single lead arranged to be projected through the opposite end. Both the magazine and the feed-tube are axially immovable, but either of them or a part thereof 30 admits of being rotated while the other remains stationary, according as to which form the invention is made to assume. An internal ejector and a hollow carrier therefor are present in all of the forms. In each 35 instance, the ejector has a positive translatory engagement with the feed-tube through the medium of its carrier, whereas the latter may be connected in various ways with the magazine, as either slidably or rotatably, 40 or in both a sliding and revoluble manner. In the first form of the invention shown in the drawing hereto annexed, the feed-tube is arranged to turn with the point of the holder and to draw out the ejector by 45 wardly translating the carrier thereof, which is in simple sliding engagement with the magazine. In the modified form next following in the illustration, the feed-tube is rendered stationary, but the ejector is 50 again advanced thereby, owing to a connection between its carrier and the magazine which is both translating and revoluble. In the second modification illustrated, the 55 feed-tube and the magazine can be given each a rotary movement serving to impel the ejector, either singly or conjointly, always through the agency of its said carrier, which is so connected with the magazine that it may have a plain sliding motion in 60 and out of it, and also a supplementary translating movement of rotation therewith.

The advantages of the invention as here outlined are best realized when all of its 65 features and instrumentalities are com-

bined in the one and same structure, but, useful devices may be produced embodying less than the whole.

It will be obvious to those skilled in the art to which the invention appertains, upon becoming conversant with the details thereof, that the same may be incorporated in several different constructions. The accompanying drawing, therefore, is submitted merely as showing the preferred exemplifications of the invention.

Referring to Figs. I, II and III, for a detailed description of the first form of the invention hereinabove spoken of, the numeral 1 denotes an outer casing or shell, 70 conveniently made cylindrical in shape, and preferably of uniform cross-sectional area throughout its body or main portion. This casing may be manufactured from sheet-metal, in any approved manner, style, and 75 fashion.

At its forward end, the said casing 1 is fitted with a conical member 2, that constitutes the tip of the holder, the same terminating in a point 3, through which is 80 provided a central hole or opening, as at 4, for the insertion and subsequent outward feed of an ordinary pencil lead 5 of a size sufficiently small diametrically not to require sharpening. The member 2 may be joined to the casing in any suitable manner. As shown, these two parts are united simply by a crimp in the metal of which they are composed, producing interconnected ridges 6, 7, that permit the rotation of the conical 85 member relative to the casing, and conversely.

Provision is made for storing a number of pencil leads in the rear end of the holder, to replace eventually the one used up at the 90 tip or forward end. For that purpose, a magazine 10, consisting of fluted sheet-metal, is inserted in the rear end of the casing 1, which thus surrounds a series of peripheral pockets 11, adapted to contain the leads separated individually from one another. The apices or outwardly-projecting fluted portions of the metal may be soldered to the inner surface of the casing so as to retain the magazine in fixed position. The inner extremities of the pockets are also turned laterally outward, as at 12, to keep the leads within the magazine. The pockets are covered up normally by means of a cap or stopper 13. This cap, as shown, 110 snugly fits the rear end of the casing, and is provided with an inner flange 14, extending over the outer extremities of the pockets. Externally, the cap may be formed with a bead 15, adapted to bear against the 115 edge of the casing, at the extreme rear end thereof, when the cap or stopper is entered into the same.

A guide 18, preferably of tubular form, is provided in the forward portion of the 120

holder, for the lead 5 to project through in the usual manner. This tubular guide is positioned centrally within the holder, and in axial alignment with the opening 4, in 5 the tip of the conical member 2, to which it is soldered endwise or otherwise secured, so that it will turn therewith whenever the said member is rotated relatively to the casing.

10 Back of the pencil lead in the tube 18, is an ejector 21, consisting of a slender rod fitting the bore of the tube. This ejector, it is understood, slidingly engages the tubular guide, in order to push the lead there- 15 through and cause it to project out of the opening 4, as wanted for purposes of writing. Both the guide and the ejector may be of same length as the lead, or approxi- 20 mately.

20 The ejector aforesaid is enclosed for nearly its entire length by a hollow or tubular carrier 22, of which it constitutes the central axis. The tube forming the carrier has a bottom 23, to which the rear end of 25 the ejector is attached, and forwardly the mouth of the latter-named tube takes over the inner end of the guide 18, into which the ejector is directed. The guide is externally threaded, as at 24, and engaged by 30 a corresponding internal thread 25, in the said mouth of the tubular carrier.

Preferably, the before mentioned carrier 22 is made of polygonal contour, that is, with a plurality of outwardly-disposed faces 35 28, arranged to bear slidingly upon inwardly-presented portions 29, of the fluted or corrugated tubing that forms the magazine 10. The faces 28 and bearing portions 29, it will be noted, are shown as being flat 40 or straight in outline, but this is not an essential feature, as these parts could easily be given some other shape that would answer the same requirements. Taken together, the bearing portions 29 constitute 45 for the carrier 22, a confining space or chamber 30, which may be closed at the outer end by a transverse partition 31 to prevent disassociation of the carrier from the lead guide.

50 Due to the construction and arrangement of parts now particularly described, it will be seen that the guide 18, containing the lead 5, the aligned ejector 21, the carrier 22 thereof receive mutual support from the 55 magazine chamber 30, while permitting a contemporaneous movement of the operative elements in an axial plane of the holder. As will be observed, the pencil lead is projected outwardly by the ejector whenever 60 the conical member 2 is rotated relatively to the casing 1, causing the tubular guide 18, through the action of the screw-thread connection 24, 25, to slide the carrier 22 forwardly from its recess in the magazine.

65 The alternative embodiment of the inven-

tion represented by Figs. IV to VII, inclusive, comprises a casing 1^a, having a tapering end 2^a, terminating in a tip or point 3^a, all formed integrally with one another. The usual opening 4 is provided in the tip, 70 for the lead 5. The opposite end of the casing 1^a contains a magazine 10, similar to that previously described, having peripheral pockets 11, the inner extremities 12 of which are directed laterally outward to support 75 the corresponding ends of the extra pencil leads that will be stored in the magazine. As in the before described construction, the latter is covered by a cap 13, formed with a flange 14, that extends over the outer ends 80 of the pockets 11, and having also a bead 15, arranged to bear upon the extreme outer edge of the casing.

In this modified embodiment of the invention, the tubular lead-guide, designated 85 by the reference symbol 18^a, is fixed within the pointed end of the casing 1^a; so that it is devoid of any capacity for independent rotative movement. Internally, however, there is no change in the structure, as first 90 mentioned, the tube 18^a having a plain axial bore adapted to receive the ejector 21.

Exteriorly, the said tube or tubular guide 18^a is formed with a plurality of faces, as 95 24^a, adapted to engage a correspondingly-faced passage 25^a, in a hollow or tubular carrier 22^a. This modified form of carrier has a plain bottom 23, to which the ejector is secured endwise, in the manner and for the purpose hereinbefore explained.

100 It is intended, in this modification, to slide the carrier 22^a along the mouth of the tubular guide, in order to advance the ejector 21 through the latter, to feed the lead 5 outward, in the manner required. To that end, the carrier 22^a is externally threaded, as at 35, and made to engage an internally-threaded portion 36, of a rotatable member 37, centrally fitted in the magazine 10. The member 37 is preferably tubular, and is 110 prevented from having any longitudinal movement relatively to the magazine, by means of a circumferential retaining clasp 38, which may consist of a simple wire ring lodged in semi-circular grooves 39, 40, respectively formed in opposite portions of the magazine 10 and of the rotatable member 37. Outwardly, the member is circular and fitted to revolve within bearing portions 29^a, projecting there around from the 115 fluted tubing of which the magazine is composed. The clasp 38 which is preferably a split, expandable ring, is lodged in one of the grooves, for instance 40, in a compressed state, that is, with its ends closed together, 120 and after the member 37 is pushed into place within the inner walls 10 of the magazine, this ring expands automatically and engages the companion groove 39 so that further axial movement of the member 37 is pre- 125 130

vented, unless an excessive strain is applied thereto.

Rotation of the member 37, over the carrier 22^a for the ejector, is readily effected 5 through the instrumentality of the cap 13. As shown, the cap, in the present modification, is provided on the under side with a socket 43, engaging a plug or head 44, tightly entered in or forming part of the 10 outer end of the rotatable member. The socket and the plug, it will be noticed, are of polygonal configuration, being respectively formed with a plurality of flat faces 45, 46, that are interengaged and coact in 15 revolving the member 37, and the parts controlled thereby, whenever the cap 13 is turned.

It is now apparent that when a movement 20 of rotation is imparted to the cap 13, in the said modified form of the holder, the same is immediately transmitted to the member 37, which in turn slides the carrier 22^a, causing it to advance over the fixed tube 18^a, and concomitantly urging forward the pencil 25 lead therein thru the agency of the ejector 21. The effect is identical with that obtained by turning the tip of the holder in the structure hereinbefore described.

Figures VIII and IX represent a structure 30 embodying essentially the two modes of construction already described. In this structure, the casing of the holder is the same as in the first described construction, and therefore is denoted by the reference 35 numeral 1. As in the first instance, this casing is shown provided with a rotatable conical member 2, having a tip 3, in the end of which is the opening 4, for the pencil lead 5. The casing and its conical member are interfitted for rotation by means of the ridges 6 and 7, as previously set forth.

In this second modification, a magazine 10^a is employed, which differs in some respects from the one forming part of the 45 preceding constructions. The magazine 10^a preferably consists of a cylindrical body having a number of longitudinal bores 11^a, wherein the extra pencil leads can be stored. This cylindrical body is fitted in the rear 50 end of the casing 11 so as to be rotatable therein, and is arranged to bear at its inner end upon a partition 12^a, that replaces the outwardly-turned extremities of the pockets in the first form of the magazine. At the 55 outer end, the magazine 10^a is surrounded by a flange 48, arranged to bear upon the edge of the casing, at the rear terminal.

The outer end of the magazine 10^a is further formed into a socket 50, adapted to receive an eraser 51, topping the extreme rear 60 end of the holder. The socket is of sufficient depth to afford a convenient hold on the sides thereof enabling the user to rotate the magazine whenever there is occasion to 65 do so, as will presently be explained.

As in the first form of the invention previously described, the tubular guide 18 is made rotatable with the tip 2 of the casing 1, and is threadedly engaged by the open end of the carrier 22, that operates to impel forward 70 the ejector 21, the latter being secured endwise to the closed end 23 of the carrier. Therefore, the carrier is drawn forwardly with the ejector, when the tip 2 is rotated so as to turn the tubular guide. In 75 addition to this, the carrier is made rotatable with the magazine 10^a, in the second modified form of the invention now under consideration. For the latter purpose, the magazine is formed with a central polygonal recess 80 or chamber 54, and the carrier is provided with corresponding faces 55, slidably fitted therein. Hence, it will be seen that the rotation of the magazine 10^a causes the carrier to revolve simultaneously, and therefore 85 to advance over the tube 18, even though the latter be at rest. It will further be perceived that both the magazine 10^a and the tube 18 can be rotated at the same time, in which case a double advance of the carrier and 90 ejector will take place. The carrier, it will be noted, slides out of the magazine, whether or not it is rotated therewith, the sliding being due to the screw-threaded connection 95 with the tubular guide.

While certain preferred embodiments of this device have been shown and described, it will be understood that changes in the form, arrangements, proportions, sizes and details thereof may be made, without departing from the scope of the invention as defined by the appended claims.

Having described my invention what I desire to secure by Letters Patent and claim, is:—

1. A pencil lead holder comprising in combination a casing, a lead guide at one end thereof, an ejector entering said guide, a hollow carrier enclosing said ejector, one end of the latter being supported from the former, the other end of said carrier taking over the lead guide, and means for translating the carrier within said casing to cause the ejector to project the lead.

2. A pencil lead holder comprising in combination a casing provided with a rotatable element, a lead guide coaxial therewith, an ejector engaging said guide, at one end, a hollow carrier fitted over the same end of the lead guide covering said ejector, 110 and means serving to translate said carrier along the guide thru rotation of said element while the latter and said casing are maintained in the same longitudinal relation.

3. A pencil lead holder of constant length comprising in combination a casing, a tubular lead guide extending inwardly thereof, an ejector capable of impelling the lead thru said guide from its inner 125 130 135

end, a carrier for said ejector enclosing said inner end of the guide so as to move relatively thereto conjointly with the ejector for the major part of the same, 5 and means for translating said carrier over the lead guide within said casing from either end of the latter.

4. A pencil lead holder comprising in combination a casing, a magazine for pencil leads at one end thereof, a tubular guide for a single lead at the opposite end, an ejector arranged to project the lead in said guide, a hollow carrier for said ejector axially movable thru said magazine into engagement with and enclosing the lead guide at the same end of the casing, and means for translating said carrier over the guide out of the magazine.

5. A pencil lead holder comprising in combination a casing, a tubular lead guide extending into the same from one end thereof, a magazine for pencil leads positioned at the opposite end of said casing, a carrier translatable from within said magazine so 25 as to take over said guide, an ejector caused to engage the latter from the interior of said carrier, and an element at one end of the casing capable of imparting axial movement to the conjoined carrier and ejector.

30 6. A pencil lead holder comprising in combination a casing, a magazine for pencil leads positioned within the head portion thereof, a coaxial tubular guide for a single lead extending inwardly of said casing, an 35 ejector slidably engaging said guide so as to project the lead therethru, a hollow carrier for said ejector movable in axial relation interiorly of said magazine in position for exteriorly engaging the guide, and 40 means operable from one of the ends of the casing for imparting translatory movement to the carrier.

7. A pencil lead holder comprising in combination a casing having a rotatable 45 member at the point thereof, a centrally recessed magazine for pencil leads at the other end of said casing, a tubular lead guide secured inwardly to said member so as to be rotated thereby, an ejector entering said

guide, an enclosing carrier for said ejector 50 taking over the guide from the recess in said magazine, and an operable connection between the guide and the carrier effecting a translatory movement of the latter upon interrelative rotation of the casing and its 55 member.

8. A pencil lead holder comprising in combination a casing with a pointed end, a tubular lead guide extending inwardly from the same, an ejector arranged to project the 60 lead thru said guide from the inner end thereof, a carrier to which said ejector is secured engaging and enclosing the lead guide, a centrally recessed magazine for pencil leads located in the head portion of 65 said casing, a rotative element beyond said magazine, and means intermediate of said element and said carrier serving to convert rotary motion imparted to the former into axial translation of the latter over the lead 70 guide.

9. A pencil lead holder comprising in combination a casing having a rotatable member at one end thereof, an internally recessed magazine for pencil leads at the 75 opposite end of said casing, a tubular guide for a single lead extending from said member coaxial with the recess in said magazine, a hollow carrier axially movable with relation to the latter in position to take over 80 said guide, an ejector supported from the interior of said carrier adapted to enter the guide, and a connection between the carrier and the guide capable of translating the former upon rotation of either the casing 85 and the member or both of them to cause the ejector to project the lead.

10. In a pencil lead holder, the combination of a casing and a member rotative relative to each other; a screw co-axial with 90 and fixed in said member and having a longitudinal bore; a carrier telescoping in and rotative by said casing and having internal screw threads engaged by said screw; and an ejector permanently attached to said 95 carrier and adapted to traverse the bore of said screw.

WILLIAM N. O'ROURKE.
